UNITED STATES PATENT OFFICE.

FRANK M. FABER, OF PITTSBURG, PENNSYLVANIA, ASSIGNOR TO WILLIAM S. ELLIOTT, OF PITTSBURG, PENNSYLVANIA.

TUBE-CLEANER.

No. 807,918.

Specification of Letters Patent.

Patented Dec. 19, 1905.

Original application filed March 10, 1903, Serial No. 147,068. Divided and this application filed July 20, 1903. Serial No. 166,235.

To all whom it may concern:

Be it known that I, FRANK M. FABER, of Pittsburgh, Allegheny county, Pennsylvania, have invented a new and useful Tube-Cleaner, 5 of which the following is a full, clear, and exact description, reference being had to the accompanying drawings, forming part of this specification, in which—

Figure 1 is a side elevation of my improved 10 cleaner-head, and Fig. 2 is a cross-section on the line II II of Fig. 1.

My invention relates to the class of tube-cleaners of the Elliott type, wherein a fluid-actuated turbine is connected to a head or stem 15 having freely-swinging longitudinal arms with transverse cutters mounted thereon; and the object of the invention is to provide wings and stops for the swinging arms which shall prevent excessive wear and improper positioning 20 of these arms in the tubes.

This application is a division of my former 25 application, Serial No. 147,068, filed March 10, 1903.

In the drawings, 2 and 3 represent the freely- 30 swinging arms, of which I have shown four, arranged in opposite pairs, the arms 2 being longer than the other pair and all of them being pivotally connected to a rotatory block 4, having a universal-joint connection 5 with the 35 stem of a turbine. The arms are free to swing under the action of centrifugal force, and the universal joint may or may not be used, though I prefer to employ it.

The arms 2 are provided with inwardly-projecting stops 6 and below them with oppositely-projecting lateral guide-wings 7. The arms 3 are provided with upper oppositely-projecting lateral wings 8, which engage the side faces of the stops 6, and below the same with 40 inwardly-projecting stops 9, which in turn are engaged by the side wings 7 of the arms 2. Each arm is therefore provided with a projection which engages with wings on the adjacent arms and also with wings which engage a projection on the adjacent arms.

When the device is inserted in the tubes, the 45 arms are restricted in their outer movement by the walls of the tube, so that the ends of the radial inner projections do not move outwardly beyond the edges of the wings, while the inward motion of each arm is limited by the engagement of its wings with the projections on

the adjacent arms, so that the opposite cutters can never contact with each other nor with the arms carrying other cutters. Efficient action 55 is thus afforded and the arms and cutters are prevented from injuring each other.

The arms are provided with the transverse toothed cutters 10, as in the Elliott type, and these wheels may either be conical, as shown, 60 or cylindrical.

The advantages of my invention result from the peculiar arrangement of the stops and guides, which hold the arms in proper position, limit the inward swing, and prevent their 65 injuring each other.

Many variations may be made in the form and arrangement of the cleaner, the arms, stops, &c., without departing from my invention.

70

I claim—

1. A tube-cleaner having swinging arms each provided with a square-sided stop arranged to contact with the inner side of an adjacent arm to positively limit the inward movement of said arms; substantially as described. 75

2. A tube-cleaner having swinging arms, at least one arm having an inwardly-projecting guide, the adjacent arm having a side wing arranged to engage the side face of said projection; substantially as described. 80

3. A tube-cleaner having swinging arms, each arm having an inwardly-projecting guide, and a side wing, the side wing of each arm being arranged to engage the side face of 85 the inwardly-projecting guide of the adjacent arm; substantially as described.

4. A tube-cleaner having swinging arms arranged in pairs, each pair having inwardly-projecting lugs at one level and side wings at 90 another level, the wings of one pair engaging the side faces of the lugs on the other pair; substantially as described.

5. A tube-cleaner having swinging arms, cutters at the free ends of said arms and co- 95 acting stops and wings on said arms to prevent contact of the cutters with each other or with adjacent arms; substantially as described.

In testimony whereof I have hereunto set my hand.

FRANK M. FABER.
